UNITED STATES PATENT OFFICE.

JAMES E. ROMIG, OF ROSLYN, PENNSYLVANIA.

CONTAINER.

1,360,688.

Specification of Letters Patent. Patented Nov. 30, 1920.

Application filed May 28, 1920. Serial No. 384,840.

To all whom it may concern:

Be it known that I, JAMES E. ROMIG, a citizen of the United States, residing at Roslyn, county of Montgomery, and State of Pennsylvania, have invented certain new and useful Improvements in Containers, of which the following is a specification.

One object of my invention is to provide an improved container which is particularly adapted for use as a barrel and which can be easily put together and taken apart without the use of nails, screws or similar devices.

Another object is to make my improved container in such manner that it will be strong and durable and can be easily and cheaply manufactured.

A further object is to so construct my improved container that it can be used as a "knockdown" container for shipping purposes.

These objects, and other advantageous ends which will be described hereinafter, I attain in the following manner, reference being had to the accompanying drawings in which—

Figure 1 is a perspective view of my improved container in the form of a barrel; the same being shown closed and ready for shipment.

Fig. 2 is a central sectional elevation of my improved barrel and taken on the line 2—2 of Fig. 3.

Fig. 3 is a sectional plan view taken on the line 3—3 of Fig. 2.

Fig. 4 is a sectional perspective view showing a modified form of certain of the parts of my improved container, and

Fig. 5 is a fragmentary sectional perspective view showing another modification of my invention.

Referring to the drawings and particularly to Figs. 1 to 3 inclusive, my improved container includes a base section 6 made in the form of a continuous ring which may be constructed of stamped or pressed sheet metal; the same including an integral base plate 7 having a flange 8 which includes a depending portion 9 and an upwardly extending portion 10 which surrounds the portion 9 so as to provide an annular groove 11 having a part projecting below the base plate 7 as clearly shown in Fig. 2. In other words the flange 8 is substantially U-shape in cross section and a part 12 of the outer portion 10 projects above the top of the base

plate 7. A top ring section 13 is also provided and is preferably made of pressed or stamped sheet metal and includes an inwardly depending flange 14 in the form of an inner band and an outwardly depending integral flange 15 which is spaced from the flange 14 to provide a groove 16 which is closed at its top by the portion 17 which connects the flange 14 with the flange 15. In other words, the top ring section 13 includes the upwardly extending annular groove 16 which is opposed to the groove 11 of the base section 6. The lower part of the flange 14 has an inwardly bent portion 18 which provides a ledge which extends circularly to form an opening 19.

Staves or slats 20, which may be made of wood, are arranged in annular formation and have their lower ends snugly fitting within the groove 11 and their upper ends snugly fitting within the groove 16. The upwardly extending portion 10 of the flange 8 has loops 21 formed therein preferably by cutting the metal and bowing the parts between the cuts as clearly shown in Fig. 1. These loops or eyelets 21 are spaced preferably at equal distances apart and in the present instance I have illustrated four of these loops within the circumference of the flange. In similar manner the outer flange 15 of the top ring section 13 has loops or eyelets 22 formed therein which are preferably arranged to be disposed directly above the intervening spaces between the loops 21 of the base section flange portion 10. A single length of wire 23 is laced in zig-zag manner through the eyelets 21 and 22 so that the strands of the wire alternate between the base section and the top ring section. The ends of the length of wire 23 may be twisted together as shown at 24 so as to secure the parts together. A circular cover plate 25 has a depending flange 26 which is adapted to fit within the space provided by the flange 14 of the top ring section 13 and the lower edge of said plate 26 is adapted to rest upon the ledge 18; the construction preferably being such that the top surface 27 of the cover plate 25 is flush with the top 17 of the ring section 13. The cover plate 25 has loops 28 which are preferably formed by cutting and pressing the metal thereof upwardly and these loops form eyelets to permit another length of wire 29 to be laced therethrough; said wire 29 also being laced in a zig-zag manner through the alternating loops or

eyelets 22 of the top ring section as clearly shown in Fig. 1. The ends of the wire 29 may be twisted together as shown at 30 and in this manner the container is securely closed for purposes of shipment.

In Fig. 4 I have shown a structure which is substantially similar to that shown in Figs. 1 to 3 inclusive with the exception that instead of forming the eyelets by looped parts of the top ring section and cover plate, the eyelets 22^a and 28^a are produced by cutting and bending integral ears from the parts; said ears including holes 31 through which the wires may be laced. In all other respects the construction is similar to that described in connection with Figs. 1 to 3 and I have therefore given similar parts corresponding reference numerals.

In Fig. 5 I have shown a construction similar to that described in connection with Figs. 1 to 3 inclusive with the exception that instead of providing the top cover plate with a depending flange fitting within the space provided by the flange 14, the top cover plate 25^a rests directly on the top 17 of the ring section 13. In all other respects the construction of Fig. 5 is similar to that described in connection with Figs. 1 to 3 and I have therefore given similar parts corresponding reference numerals.

By making a container as above described the base and top sections can be quickly and cheaply manufactured and the staves can be inserted first in the groove 11 and then the top ring section can be placed over the annularly arranged top ends of the staves so as to fit within the groove 16. As previously stated the staves are adapted to fit snugly within said grooves so that a firm and strong construction will be provided and when the wire 33 is laced as described and the ends twisted together, an extremely strong structure will be provided. The container can then be filled and the top cover plate applied and laced and when thus secured together the container can be shipped great distances and roughly handled without the several parts becoming loose or in any way displaced. If desired the several sections can be taken apart and stored in a comparatively small space such for example as when desired for use for cargo shipment in one direction and in which the empty containers must be returned.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. A container including end sections spaced apart and provided with opposed annular grooves; staves having opposite ends arranged respectively within said grooves; and common lacing means connecting said sections together and surrounding said staves; substantially as described.

2. A container including end sections spaced apart and provided with opposed annular grooves; staves having opposite ends arranged respectively within said grooves; and a wire in laced connection between said end sections whereby said end sections are prevented from moving apart; substantially as described.

3. A container including end sections spaced apart and provided with opposed annular grooves; staves having opposite ends arranged respectively within said grooves; said end sections having eyelets; and a wire laced through the eyelets of both sections and having its ends secured together; substantially as described.

4. A container including end sections spaced apart and provided with opposed annular grooves; staves having opposite ends arranged respectively within said grooves, said end sections having eyelets; and a wire laced in zig-zag form alternating between the loops of the top and bottom sections, said wire having its ends secured together; substantially as described.

5. A container including end sections spaced apart and provided with opposed annular grooves; staves having opposite ends arranged respectively within said grooves, one end section including an opening and having eyelets; a cover plate for said opening having eyelets; and a wire laced through the eyelets of the cover plate and said section; substantially as described.

6. A container including end sections spaced apart and provided with opposed annular grooves; staves having opposite ends arranged respectively within said grooves, one end section including an opening and having eyelets; a cover plate for said opening having eyelets; and a wire laced through the eyelets of the cover plate and said section, said section having an inwardly projecting ledge, said cover plate having a flange adapted to rest upon said ledge; substantially as described.

In testimony whereof I have signed my name to this specification in the presence of two subscribing witnesses.

JAMES E. ROMIG.
